(57) **CLAIM**

The ornamental design for a paint roller cleaning device, as shown and described.

DESCRIPTION

FIG. 1 is a top perspective view of a paint roller cleaning device, showing my new design.

FIG. 2 is a bottom perspective thereof.

FIG. 3 is a front view thereof.

FIG. 4 is a rear view thereof.

FIG. 5 is a left side view thereof.

FIG. 6 is a right side view thereof.

FIG. 7 is a top plan view thereof; and,

FIG. 8 is a bottom plan view thereof.
